DESIGN FOR A DRESS

Louis Kushman, New York, N. Y.

Application October 19, 1939, Serial No. 87,715

Term of patent 3½ years

To all whom it may concern:

Be it known that I, Louis Kushman, a citizen of the United States of America, residing in the city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

The characteristic feature of my design resides in the combination on the specific dress disclosed of the specific contrasting strips on the waist portion in association with the matching inserts on the skirt as shown.

I claim:

The ornamental design for a dress, substantially as shown and described.

LOUIS KUSHMAN.
